(57) CLAIM

I claim the ornamental design for a ornamental lighted display, as shown and described.

DESCRIPTION

FIG. 1. Is a front perspective view of our ornamental lighted display;

FIG. 2. Is a front view thereof;

FIG. 3. Is a top plan view thereof;

FIG. 4. Is a bottom plan view thereof;

FIG. 5. Is a back view thereof; and,

FIG. 6. Is a right view thereof, the left side view being identical to that shown.

The broken line portions of the disclosure are for illustrative purposes only and form no part of the claimed design.
